UNITED STATES PATENT OFFICE

PETER AURICH, OF BOCHUM, GERMANY, ASSIGNOR TO THE FIRM GEBR. EICKHOFF, MASCHINENFABRIK, OF BOCHUM, GERMANY

SHAKING CONVEYER

Application filed July 7, 1927, Serial No. 204,064, and in Germany January 28, 1927.

The invention has for its object to improve conveyers of the shaking type, as used for instance, in mining service.

In operating conveyers mounted on very uneven ground, not only forces arise, acting in upward direction and tending to buckle the conveyer, but also forces which act in an oblique lateral direction and tend to bend the conveyer laterally. These forces seriously impair the accurate running of the conveyer.

Now my invention has for its object to obviate this drawback. This object is attained by the fact that, besides means which guide the conveyer in vertical direction and prevent it from being lifted, further means are provided that take up the forces acting in lateral direction and secure an accurate rectilinear motion of the conveyer.

In order to allow my invention to be more easily understood, a preferred embodiment of same is illustrated by way of example in the drawing which accompanies and forms part of this specification. In this drawing:

Fig. 1 is an elevational view of the improved conveyer,

Fig. 2 is the corresponding top plan view, whilst

Fig. 3 is a fragmentary side elevation thereof.

Referring now to these figures, *a* denotes one of the supporting brackets of the conveyer which bracket may be fixed, according to the conditions prevailing, by means of props *s* or by bolts screwed into a suitable foundation. Antifriction rollers *b* are mounted so as to rotate in vertical planes on the bracket *a*, and engage horizontal groove-shaped longitudinal guides *d* provided on the supports *r* of the conveyer trough. Furthermore, the brackets *a* carry one or more lower antifriction rollers *c* which rotate in a horizontal plane and engage a groove-shaped guide *e* likewise extending in the longitudinal direction of the conveyer and fixed on the underside of the latter.

The rollers *b* thus guide the conveyer in vertical direction and prevent it from being lifted, whilst the rollers *c* guide it laterally

and take up the forces acting in a lateral or oblique direction.

Of course, instead of being arranged on the bracket, the rollers *c* may be mounted on the conveyer whilst the guides *e*, *e* are fixed on the bracket. In case the vertical guide members *b*, *d* extend in a curved line, the lateral guide members *c*, *e* are of a design so as to remain in mesh both in the uppermost and lowermost position of the conveyer trough occurring in its reciprocating motion.

The described supporting structure is further very well suited to be combined with the motor that actuates the conveyer, as it is capable of taking up in a favorable manner the obliquely directed forces exerted by the motor. When used in this manner, at least two antifriction members are preferably provided for on each side, between which members the motor is attached to the trough, or a bracket is arranged before and another bracket behind the point where the motor is attached to the conveyer.

What I claim and desire to secure by Letters Patent is:—

1. In a shaking conveyer, in combination, a longitudinally reciprocable trough member, a trough supporting bracket member, means between the bracket member and the trough member for guiding the latter in the direction of reciprocation, a horizontally disposed roller journalled on one of the members, and a longitudinally disposed guide on the other member coacting with the horizontally disposed roller for guiding the trough member against lateral displacement.

2. In a shaking conveyer, in combination, a longitudinally reciprocable trough member, a trough supporting bracket member, vertically disposed rollers journalled on one of the members, longitudinally disposed guides on the other member coacting with the vertically disposed rollers for guiding the trough member in the direction of reciprocation, a horizontally disposed roller journalled on one of the members, and a longitudinally disposed guide on the other member coacting with the horizontally disposed roller for guiding the trough member against lateral displacement.

3. In a shaking conveyer, in combination, a longitudinally reciprocable trough member, a transversely disposed member extending underneath the trough member and having vertically positioned bracket portions extending upwardly on each side of the trough member, anti-friction means disposed between the bracket portions and the sides of the trough for guiding the trough in the direction of reciprocation, and independent anti-friction means between the bottom of the trough and the main portion of the bracket member for guiding the trough against lateral displacement.
4. In a shaking conveyer, in combination, a longitudinally reciprocable trough member, longitudinally extending guides of U-shape cross section secured to the trough member in the vicinity of the sides thereof, horizontally journalled vertical rollers on the bracket members inserted into the U-shape guides, a longitudinal double guide on the bottom of the trough member, and a vertically journalled horizontal roller on the bracket member inserted between the portions of the double guide.

In testimony whereof, I have signed my name to this specification.

PETER AURICH.
